United States Patent Office

Des. 232,177
Patented July 23, 1974

232,177

FLAG STAND

Joseph S. Craig, Marion, Iowa
(530 4th Ave. E., Cresco, Iowa 52136)

Filed Sept. 5, 1972, Ser. No. 286,564

Term of patent 14 years

Int. Cl. D11—05
U.S. Cl. D29—17 A

The figure is an overhead isometric view of a flag stand showing my new design.

I claim:

The ornamental design for a flag stand, substantially as shown and described.
